UNITED STATES PATENT OFFICE.

PHYLANDER DANIELS, OF LE ROY, NEW YORK.

IMPROVEMENT IN ARTIFICIAL LEGS.

Specification forming part of Letters Patent No. 41,282, dated January 19, 1864.

To all whom it may concern:

Be it known that I, PHYLANDER DANIELS, of Le Roy, in the county of Genesee and State of New York, have invented certain new and useful Improvements in Artificial Legs; and I do hereby declare that the following is a full and exact description thereof, reference being had to the accompanying drawings, making part of this specification.

Figure 1 is a central vertical section of my improved leg; Fig. 2, a central vertical section of the knee-joint at right angles to Fig. 1; Fig. 3, a central vertical section of the ankle-joint at right angles to Fig. 1; Fig. 4, an elevation of a portion of the foot and leg, showing more particularly the arrangement of the ankle-joint.

Like letters of reference indicate corresponding parts in all the figures.

My improvements have relation to the superior portion or thigh-socket of the artificial limb, the arrangement of the parts composing the knee-joint, to the use of a coiled, winding adjusting-spring connecting the superior and anterior portions of the leg, whereby the forward movement is produced in walking, and to the arrangement of the parts composing the ankle-joint.

As represented in the drawings, the limb is adapted to use where amputation is above the knee.

In ordinary devices the superior leg or socket A is formed of wood turned or fashioned to the proper form, and having a socket for the reception of the natural member. For different persons this portion of the limb has to be made of different sizes and forms, involving much labor and expense. It is also very heavy and unwieldy. The greatest objection is, however, that by reason of its rigidity and unyieldingness it is exceedingly painful and uncomfortable to the wearer, and this cannot be obviated by stuffing or cushioning without enlarging the socket or weakening it. To avoid these difficulties I make the superior portion of ordinary sole-leather, cut out so as to form the proper shape, and bent around with its edges uniting, and secured together by sewing or in any suitable manner. The advantages of this arrangement are that the socket thus formed is extremely light and at the same time exceedingly strong, not being subject to frac-

ture by accident, or to become weather-cracked, as in the case of wood, while it is formed at a fraction of the expense and labor. By its considerable height and its stiffness it is unyielding vertically, thus always retaining its form; but at the same time, by its flexibility, it adapts itself easily to any pressure of the natural member within it, thus securing great ease and comfort to the wearer—a matter of the greatest consequence. To the upper end of this portion is secured a strip, a, of leather, having attached thereto buckles b b for connecting supporting-straps passing over the shoulder of the wearer.

The lower open end is filled by a block, B, of wood, Figs. 1 and 2, to which the leather is secured by means of screws, nails, or otherwise. The knee-joint is formed by the junction of the inferior leg C with this block, as follows: Vertically in the block, at suitable distances apart, are made two or more saw kerfs or grooves, c c, Fig. 2, of suitable height, having rounded tops, which receive, respectively, closely thin metallic disks or circular plates D D, Figs. 1 and 2, having shanks d d, extending down into the wood of the inferior leg and secured by screws, or in some equivalent manner. Centrally through the joint thus formed passes an axis, f, secured conveniently by a nut, g. In corresponding position, near the edge of the plates D D, are made concentric slots h h, through which passes a transverse bolt, i. The relative position of the slots and bolt is such that when the leg is in a fully-upright position, as in Fig. 1, the bolt rests against the forward boundaries of the slots; but when the leg is flexed the slots are of sufficient length to allow the movement of the bolt.

This arrangement secures a very firm and unyielding joint, which cannot easily get disarranged, while it is very cheap and easily made.

The plates D, fitting and turning closely within the grooves and being situated at considerable transverse distance apart, insure the leg against any undue lateral action or strain, and thus keep it firmly in place under all circumstances and conditions, whether passing over smooth or uneven surfaces. This bracing against transverse movement is rendered more effective by the employment of the bolt

i, which prevents to a certain degree the lateral leverage from acting entirely on the axial center *f* as a fulcrum by sharing a portion itself, thus having a tendency to keep the plates from becoming bent or broken. The special use of the slots and bolt, however, is to form a gage to prevent the leg being brought forward too far, or beyond the upright position, by the reaction of the spring connecting the superior and inferior portions of the leg, as will presently be described. This is accomplished by the pin striking against the end of the slots and arresting farther motion. This device is very convenient and effective.

When the leg is flexed, the reaction to an upright position is produced by a flat coiled spring, *g*, (Fig. 1,) of suitable size, similar to an ordinary clock-spring, attached at the upper end in any suitable manner to the superior portion *A* of the leg, and passing thence downward into a cavity, *k*, in the inferior portion *C*, and winding on a small transverse drum having a ratchet-wheel, *l*, on its shaft, into which catches a pawl, *m*, substantially as represented. Thus it will be perceived that the spring may be wound or unwound by merely turning or unturning the shaft. To accomplish this action I prefer to extend the shaft *p* out through a key-hole in the side of the leg, and make that portion square, to which is fitted a key having a square socket similar to a watch-key. The reverse movement to relieve the reaction of the spring may be accomplished in any desirable manner, the arrangement represented in the drawings being a straight slide, *g*, passing in through the leg and striking against a projection of the pawl below its pivot. The front portion, *o*, of the inferior leg is made removable to secure access to the cavity *k*.

The wearer by means of this arrangement is enabled to adjust the reaction of the spring connecting the upper and lower portions of the leg to the exact degree of intensity necessary or desired, it being fully under his control. This adjustment is frequently necessary to compensate for the changes produced by difference of temperature, summer or winter, also wear, the difference in gait or quickness of step in different individuals, and many circumstances that require a modification of the flexing of the limb. By the use of this device I am also enabled to employ the same size of spring in limbs of different sizes by merely regulating its intensity in the manner described—a matter of very great convenience; and it is also adapted, in the same relation, to limbs of different height by uncoiling more or less of its length—an effect that cannot be produced in any other device with which I am acquainted, the elastic cord or spring in such cases being adapted only to a single leg, and not adjustable either in intensity or length to different limbs.

The ankle-joint is produced by a transverse

axis, *r*, passing through the inferior leg *C*, the extremities of said bolt resting in the upper end of laterally-acting hinges *s s*, Figs. 3 and 4, attached rigidly on the outside of the foot *H* on either side, but the upper half thereof, in which the axis rests, being allowed some lateral motion on its central joint, as clearly shown. The object of this arrangement is to allow the foot to incline somewhat in walking over uneven ground, or in stepping on stones or other small bodies that have a tendency to incline the foot sidewise. This effect is further insured by the peculiar formation of the socket *t*, Fig. 3, through which the axis passes. This socket is enlarged or rounded out on each side of the center, so as to leave an open space at each end for the axis to work in, the central portion only bearing, as clearly indicated. This allows either the foot or leg to turn sidewise to a suitable degree and without positive friction, the surface of the socket *t* merely rolling, as it were, upon the axis, instead of turning, as in ordinary arrangements.

I am aware that lateral action of the foot has before been attained by the use of a universal joint, and also a ball-and-socket joint; but such I do not claim.

By having the axis sustained outside the foot I obtain a greater width of bearing or support, so that the parts are more securely connected together than by any other method. By the peculiar combination of the axis and socket the central bearing-surface of the former is but slight, so that the progressive vertical motion produces but little friction, and at the same time, in turning laterally, the rolling action of the axis produces scarcely any friction.

The anterior and posterior portions of the foot are connected with the leg by means of elastic straps *u* and *v*, the former connected in a suitable manner with an adjusting-screw, *w*, in the foot, by which its reaction is adjusted to any degree desired. The axial bolt of the ankle-joint being situated equidistant between these straps, their office is to hold the foot to its proper horizontal position in relation to the leg when not in motion. In walking, when the weight is thrown on the heel, the cord *u* is elongated, and its contraction immediately restores the foot to its normal position when raised for the next step. When the weight is greatest on the forward portion of the foot, the cord *v* is elongated, and in reacting its action is like that of the other. By adjusting the tension of *u* by the screw *w*, the action may be easily and perfectly adapted to the requirements of the wearer.

I do not claim a leather socket for the reception of the natural thigh in amputation above the knee, when said socket is rigidly braced and confined by the addition of a framework of wood or iron; nor do I claim a flexible leather socket with side irons merely for the purpose of securing the leg firmly to the

natural thigh when amputation is below the knee, as I am aware that such devices have before been employed; but,

What I claim as my invention, and desire to secure by Letters Patent, is—

1. Forming the socket A, for the reception of the natural thigh when amputation is above the knee of sole-leather or other thick leather of sufficient stiffness to be self-supporting, and not requiring a skeleton frame, and so arranged that its flexibility will allow it to yield and adapt itself to the form of the natural member within, so as to secure ease to the wearer, said socket being used in combination with the block B, or its equivalent, for forming the knee-joint, substantially as herein set forth.

2. The knee-joint composed of the thin plates

D D, resting in the grooves c c, and connected by the axis f, substantially as herein described.

3. In combination with the parts thus forming the knee-joint, the concentric slots h h and bolt i, arranged substantially as herein specified.

4. The arrangement of the lateral hinges s s, axis r, and its socket t, in combination with the foot H and inferior-leg C, substantially as and for the purpose herein set forth.

In witness whereof I have hereunto signed my name in the presence of two subscribing witnesses.
